UNITED STATES PATENT OFFICE.

WILLIAM FORSYTH TORRANCE, OF DALMUIR, SCOTLAND, ASSIGNOR OF ONE-HALF TO
ARTHUR CLARK STEWART, OF CLYDEBANK, SCOTLAND.

SAFETY DEVICE FOR MINE CAGES, LIFTS, AND THE LIKE.

Application filed April 14, 1923. Serial No. 632,050.

To all whom it may concern:

Be it known that I, WILLIAM FORSYTH TORRANCE, of 21 Hillview Terrace, Dalmuir, Dumbartonshire, Scotland, engineer, have 5 invented certain new and useful Improvements in and Connected With Safety Devices for Mine Cages, Lifts, and the like, of which the following is a specification.

My invention has reference to safety devices for mine cages, lifts and the like of the kind adapted to release the cage, lift, or the like in the event of over-winding, and of the kind adapted to support the lift, cage, or the like, or prevent it falling rapidly to the bottom of the cage shaft, or lift well should the hoisting cable be broken asunder, or the cage, or lift be detached therefrom.

The object of this invention is to provide improvements in means of the above character whereby the release of the cage, or lift, is assured and is effected automatically should overwinding take place, and whereby the arrest, or braking of the fall, of a lift, or cage, should it become detached from the hoisting cable, is effected.

Under this invention, the cage, or lift, is connected with the hoisting cable by means of a hinged jaw, or equivalent device attached to the cage, or lift, and provided with 30 a recess, or recesses, adapted to receive an enlargement, or enlargements, on the hoisting cable, the connection between the cable and device being maintained by a ring, or sliding member, arranged on the hinged jaw, or equivalent, device and a spring, or the like, adapted to press the ring, or member, towards the opening end of the jaw and thereby keep the same closed, and the disconnection being effected by a rod, finger, or the like so disposed relatively to the hoisting means as to contact with the ring, or member, and press it towards the hinged end of the jaw and thereby enable the jaw to open and free the end of the hoisting cable engaged with the jaw.

Further, under this invention, the cage, or lift is provided with suitably shaped spring actuated cams hinged, or pivoted, thereto and adapted to operate against a plate, or its 50 equivalent, which is normally connected with the hoisting cable and is fitted with rollers, or other antifriction means, for bearing against the said plate, the cams being held out of operation by the said plate when the 55 cage, or lift, is suspended on the cable, and

being moved to an operative braking, or engaging, position with the cage, or lift, guides in the shaft, or well, by pins when the cage, or lift, becomes detached from the hoisting engine, such as, by the cable breaking, 60 or the release thereof from the hinged jaw, or equivalent, device which, in this arrangement is connected with the cage, or lift, by the said plate.

Preferably, the end of the hoisting cable 65 is fitted with a shackle, or ring, and the hinged jaw, or equivalent device, is hinged at its lower end to the plate connected with the cage, or lift, and comprises two corresponding members each provided with a 70 recess, or gap, which, when the jaw device is closed, are adapted to receive and retain in connection therewith, the said shackle, or ring.

In order that my invention may be properly understood and readily carried into effect, I have hereunto appended one sheet of drawings, of which—

Figure 1 is an elevation of a shaft showing the cage and my improvements applied 80 thereto!

Figure 2 is a plan of Figure 1.

Figure 3 is an elevation showing the overwinding of the hoisting rope.

Figure 4 is an enlarged view of the wedge- 85 piece as in Figure 1.

Figure 5 is a plan of Figure 4.

Referring to the drawings, S is the cage, lift or such like, A the cable or winding rope, B the hinged jaws to which the hoisting rope A is connected through the medium of the ball arrangement A'. F is the connecting rod which is attached to the winding rope A by means of the pin E which hinges the jaws B which grip the ball A'. C is the plate which is supported by the pins D and which retains the jaws B in position. C' is the device which arrests the plate C and shears the pins D thereby permitting the tension on the winding rope 95 100 A through the ball A' to force the jaws B open and release the connection between the winding engine and the cage S.

R is the double bridle or plate attached to the top of cage or lift to which are 105 connected, by bolts J, two levers I, the inner end of each of which has a horizontal slot through which a pin G passes and is slideable. The pins G connect the said levers with the member F. Between the ends of 110

the plates R are brake blocks K. The brake blocks are connected to the outer ends of the levers by pins N which operate in inclined slots M with which the plates R are provided. T are the shaft guides.

In the event of overwinding or the hoisting rope breaking, the plate C comes into contact with the device C' and shearing the pins D allows the tension on the hoisting or winding rope A, through the ball A', to force open the jaws B and thereby release the connection between the winding engine and the cage S, as seen in Figure 3. The wedges, or brakes K are at once brought into action by the released strain upon the jaws B causing the wedges, or brakes K to come into contact with the shaft guides T through the action of the levers I, thereby immediately arresting the descent of the cage S by the friction set up between the wedges, or brakes K and the shaft guides T and, forcing the wedges or brakes K tightly between the double bridle R and the shaft guides T, brings the cage S to a standstill.

I claim:—

Safety apparatus for lifts, comprising in combination with arresting means, a lift-carried double bridle having outwardly and

upwardly inclined slots near the ends and 30 having upwardly and outwardly inclined beveled ends, wedge-shaped brake blocks arranged to engage said inclined beveled ends, levers pivotally mounted on said double bridle, having longitudinal slots in their 35 inner ends, bolts connecting said brake blocks to the outer ends of said levers and arranged to operate in said inclined slots, a connecting rod, bolts connecting the same to the inner ends of said levers and arranged to operate in the slots of said levers, a pair of jaws pivotally connected to said connecting rod and having a socket formed in the opposing sides of their upper ends, a cable having a ball gripped in said socket between said jaws, a plate, and frangible pins securing said plate to said jaws to normally hold the jaws in closed gripping position, said plate being arranged to engage said 40 arresting means in the event of over-winding 45 of the cable.

In testimony whereof I affix my signature in presence of two witnesses.

WILLIAM FORSYTH TORRANCE.
